APPARATUS FOR CLINCHING LIFT LEVERS
TO CANSJohn L. Card, Baltimore, Md., assignor to Federal
Tin Company, Inc., Baltimore, Md., a corpora-
tion of Maryland

Application April 4, 1938, Serial No. 200,031

9 Claims. (Cl. 113—1)

The present invention is an apparatus for clinching lift levers to the rims of, so called, plug-top covers for cans, but may be useful for other analogous purposes.

- 5 Plug-top covers, for cans or other similar receptacles, usually designate a relatively flat cover having an up-standing perimetral rim or flange, which latter is to frictionally engage the edges of an opening in a receptacle whereby it is tightly held in closed position. The rim of the plug-top covers may be somewhat outwardly flared with respect to the body of the cover and have their upper edge rolled or crimped to provide a finished edge. It is often difficult to remove 10 these plug-covers without the aid of some implement to pry between the rolled, beaded, or crimped edge of the cover rim and the container, and often such an implement is not readily at hand.
- 15 To facilitate the easy removal of such covers, as above mentioned, a lift lever is used and sold with the can. Such lift levers are frequently not made a permanent part of the can or cover, and frequently become lost by becoming disengaged from the cover.

20 The object of the present invention is to provide means to permanently attach a lift lever to the plug-cover, particularly that type of lift lever shown and described in a United States Letters 25 Patent reissue No. 18,447, said means being simple and positive in its operation and capable of continuous operation for mass production.

25 The invention further resides in whatever is shown, described, and claimed, and particularly in the sundry details of construction, combination, and arrangement of parts, as will herein-after more specifically appear.

30 In the drawings, which show the preferred embodiment of the invention, as now devised,

35 Fig. 1 is a front elevation of the apparatus mentioned above, certain parts being broken away to illustrate the manner in which the lift levers are fed and applied to the plug-cover;

40 Fig. 2 is a top plan view of the apparatus as shown in Fig. 1;

45 Fig. 3 is a vertical longitudinal sectional view taken substantially on line 3—3 of Fig. 1;

50 Fig. 4 is a fragmentary detail view of a portion of Fig. 1 showing the other position of the lift lever feeding means;

55 Fig. 5 is a fragmentary perspective view of the means for stopping or arresting the plug-covers in the position in the machine for having a lift lever attached thereto;

Fig. 6 is a perspective view of the feeder and a part of its operating means; and

Fig. 7 is a view illustrating a plug-cover having a lift lever attached thereto and which attachment was performed by the means of this 5 invention.

The lift lever attaching means of the present invention consists of what I may term a clinching machine. The lift levers of the type used in the present machine are illustrated in Figs. 10 1, 4, and 7, and consist of a piece of metal, or other suitable material, bent upon itself at one end to form an open loop. The free end of the short legs of the loop forms an abutment to engage under the bead *b* of a plug-cover *C* while 15 the closed end of the loop forms a heel *h* which will engage and bear upon the surface of the container, thereby enabling the lift lever *L* to pry or raise the plug-cover *C* from the opening 20 in the container, when the other end of the lever 25 is raised (see Fig. 7). In order to maintain these lift levers *L* on the plug-cover, an abutment *I* is provided to cooperate with the free end of the short leg *s* for retaining the parts together. The abutment *I* may be a lug struck 30 from the lever at a point to lie adjacent the free end of the short legs of said loop and, when this lug *I* is moved or pressed toward the free end of the short leg *s* to close the space between it and said free end of the short leg *s* less than the 35 diameter of the bead *b* on the plug top, it is loosely maintained in position on the latter against accidental loss or displacement.

The present clinching machine is designed to feed such lift levers *L* and plug-covers *C* to a 40 clinching station, where the lug *I* on the lift lever will be moved or placed about the beaded, rolled, or crimped rim *r* of the plug-cover.

To accomplish the above, the present clinching machine comprises a base or bed *10* to which 45 plug-covers *C* are fed by any suitable conveying means such as an endless belt *11* (Figs. 2 and 3). The covers *C*, which are delivered onto the bed *10*, abut each other and in this way are fed forward by the on-coming covers on the moving belt *11*, said covers being guided over the bed *10* by guides *12* and *12a*. The guide *12a* is adjustable laterally through the medium of the bolt and slot connection *13* to accommodate the machine to different sizes of covers. Projecting, preferably from one side of the bed *10*, is an extension *10a* upon which is supported a frame *14* which overlies the bed *10*, said frame having a bracket extension *14a* which is secured to the 50 55

extension 10a by means of bolts 14b or other suitable means. The frame 14 is provided at its upper end with spaced bars 15, preferably extending longitudinally of the machine, and in which is journalled a drive shaft 16 operatively connected with a source of power in any suitable manner, not shown. The front vertical face of the frame 14 is provided with a guide-way 17 in which is disposed a vertically reciprocable cross-head 18. Opposite walls of the guide-way are preferably formed with V-shaped guide slots 17a for receiving a complementary vertical guide rib on the cross-head 18. One of the walls of the guide-way 17 having the slot 17a therein is composed of an adjustable block 17b so as to maintain the cross-head in proper centered position and to take up for wear. The block 17b is held in position on the frame by bolt 17c and is rendered adjustable to the bolt 17d.

The lower forward edge of the cross-heads 18 is provided with a projecting tool-holder 18a to which is secured a clinching die 19. The clinching die 19 is preferably disposed in an under cut rabbit in the projection 18a and is secured thereto at one end by a bolt 19a, there being a bolt 19b in the upper ledge forming the rabbit which will bear upon the distal end portion of the die, permitting such vertical adjustment of the die as may be desired, it being understood, of course, as can be seen from Figs. 1, 2, and 4, that the operating die face is at the distal end of the die 19.

Positioned at one side edge of the bed 10 and in cooperative opposed relation with respect to the outer end of the clincher die 19 is an associating member 20 carried on the distal end of an arm 21 keyed to a rocker shaft 22, preferably underlying the bed 10 with the arm 21 extending through a slot 23 in the bed 10. This member 20 is oscillated to and from the position shown in Figs. 1 and 2 through the medium of shaft 22 for associating the lift lever with a cover in the manner which will presently appear.

Arranged over the associating member 20 is a vertical chute 25 having the passage thereof of such dimensions as will permit the lift levers L to move therethrough in a lengthwise direction. To the upper end of the chute 25 may be suitably attached a magazine, not shown, or otherwise connected with a suitable source of supply of the lift levers, so that the same move through the chute 25 by gravity, one above the other in the manner illustrated in Fig. 1, the bottom of the chute being closed by the member 20 when the latter has fed the lift lever in position for the operation of the clinching die 19 as shown in Fig. 1. When the associating member 20 has been oscillated in a clockwise direction, as shown in Fig. 4, the lower end of the chute 25 is uncovered allowing one lift lever L to drop into position so as to be fed forward to the plug cover C and be operated upon by the clinching die 19. In order to prevent the remainder of the lift levers L from dropping when the associating member 20 is in the position shown in Fig. 4, an arm 24 is provided, pivoted in brackets 26.

The arm 24 has a loose pivotal connection, as at 27, with the associating member 20 and, when the latter is moved clockwise as shown in Fig. 4, a holding finger 28 on the arm 24 will be projected through a slot 25a in the chute 25 to contact the lift lever therein next from the bottom, thus holding all other lift levers except the lowest one in the chute against movement. By rea-

son of the pivot connection 27 when the associating member is moved in an anti-clockwise direction and to the position shown in Fig. 1, the arm 24 will be operated to withdraw the locking finger 28 from the chute 25.

The surface of the associating member 20, which contacts and cooperates with the lift levers L, is preferably fashioned in a manner the same as or similar to the contour of the lift levers so as to give them substantial support during the associating movement and prevent their twisting or turning, as well as during the clinching operation.

It is understood, of course, that the lift levers as supplied to the chute have the lugs l struck out from the body thereof so that the loop ends of the lift lever may be placed, by the member 20, under the beaded edge b of the cover C with the lug overlying said beaded edge; and that it is the function of the clinching die 19 to move the lug l toward the free end of the legs of the lift lever to embrace and loosely attach the lift lever on the rim edge of the cover C, as shown in Fig. 7. With this understood and with the assembly of the machine having been outlined above, the various parts of the machine are operated as follows:

The drive shaft 16 has keyed on its forward end a cam 30 which overlies and contacts with a roller 31 rigidly journalled in the cross-head 18. The formation of the cam 30 is such that upon each revolution of the shaft 16 the cross-head is reciprocated once, the downward movement of the cross-head being accomplished quite abruptly and quickly, the cross-head remaining in its downward position for about 60°, more or less, of the movement of the cam and, then, being returned to its upper position by compression spring 32 disposed in a recess on the under side of the cross-head and resting upon a ledge 14c on the frame 14 (see Fig. 3). Also keyed to the shaft 16 is a cam 33 on the surface of which, at diametrically opposite points, ride rollers 34 and 35, which rollers are journalled on a plate 36 having an elongated slot 37 therein surrounding the shaft 16 and by means of said slot reciprocates radially of the same. The plate 36 is connected by a link 38 to the outer end of a lever 39 fast on the rocker shaft 22.

The cams 31 and 33 are so arranged that the cam 31 will effect the downward movement of the cross-head carrying the clincher die 19 when the member 20 is in the extreme position of its associating movement, in which position the member 20 has carried the lift lever against the rim of the plug cover C and clamps the latter between it and the guide 12a, at the same time holding the lift lever in position for the lug l to be operated upon by the clinching die 19.

In order to align the plug-cover C in position to have a lift lever attached thereto a stop 40 is provided which engages preferably with the rear side of the plug-cover being advanced into position. This stop 40 is carried on an arm 41, having one end fast on a shaft 41a journalled in a bracket 42 attached to one side of the base or bed 10. The shaft 41a is actuated through a bell crank lever 43 pivoted on the bracket 42 and having one arm thereof arranged to engage a lug 41b keyed on the shaft 41a and its other end pivotally connected to the cross head 18, preferably, by means of a yolk 43a surrounding a stud 44 on the crosshead. By this construction, the stop 40 is raised out of the plane of the plug-cover C when the cross-head 18 is moved down.

wardly for the clinching operation; and it is preferred that the cams 30 and 33 be so timed as to allow the associating member 20 to move backwardly (or in clockwise direction) to release the plug cover C while the clinching die 19 dwells in its clinching position for about 60° of the movement of the cam 30.

During this time the stop 40 has been raised out of the plane of movement of the plug-covers 10 C, and the friction between the clinching die 19 and the lug l of the lift lever L is so slight that, with the associating member 20 moved backwardly to release the plug cover, the friction between the plug-cover C on the conveyor is sufficient to cause the latter to abut and move the covers C on the bed 10 forwardly, thereby advancing the cover, to which a lift lever has just been applied, out of the machine and moving the next cover C to clinching station so as to have a 20 lift lever applied thereto.

By this time, the crosshead 18 has started to move upwardly causing the stop 40 to be moved in the plane of the cover being advanced in position for clinching operation. The rear inner side 25 of the rim r of said cover C will strike the stop 40, thus aligning the cover in proper position for the clinching operation. After the cover has been so stopped and aligned, and in the meantime a lift lever L having dropped from the chute 25 in front of the associating member 20, as shown in Fig. 4, the member 20 will be moved toward the cover C (or in an anti-clockwise direction) placing the lift lever in position with respect to the beaded edge b at the rim of the cover, as shown 35 in Fig. 1, following which the crosshead will move the clincher die 19 downwardly for a distance sufficient to bend the lug l of the lift lever so as to clinch the latter about the bead b of the plug-cover C. After this operation the cycle above 40 described is repeated.

In order to accommodate the stop 40 to plug covers of different sizes the lever 41 is adjustable along the shaft 41a by means of a set screw 45 and the stop may be adjustable longitudinally of 45 the lever 41, such as through means of an elongated longitudinal slot 41c in said lever through which a reduced shank of the stop 40 extends and is held in position by a nut 41d threaded on said shank, see Fig. 5.

Having thus described the invention and the manner in which same is to be performed, it is to be understood that the invention is not to be limited to the exact details of construction, combination, and parts herein described because the 55 same may be varied and modified in numerous ways and incorporate other embodiments which fall within the scope of the appended claims.

That which is claimed is:

1 In a machine for applying lift levers to the 60 rolled or beaded edges of plug caps useful for closing containers and wherein each lift lever includes a handle portion having two spaced abutments disposed near an end and laterally thereof, one of said abutments being a lug adjacent the 65 other of said abutments to cooperate therewith for attachment to the rim edge of the cover lying between said abutments, said machine comprising means for feeding caps to a clinching station, means for feeding one lift lever at a time to the clinching station and presenting the lift lever to the cap with the rolled rim edge of the cap extending between said abutments, a reciprocable clinching die at said station for bending said lug abutment toward an opposing portion of said rim 70 edge for a distance to loosely confine the rolled

portion of the rim edge between said abutments so that the lift lever is pivotally attached to the rim of the cap.

2. In a machine for applying lift levers to the rolled or beaded edges of plug caps useful for closing containers and wherein each lift lever includes a handle portion having one end bent upon itself to form an open loop having spaced legs and the handle portion further having a lug thereon beyond the free end of one of said legs of the loop 10 and extending laterally therefrom and adjacent the free end of said leg of the loop to cooperate therewith when said lug is bent toward said free end of said leg of the loop with the rim edge of the cover between it and the free end of said leg 15 of the loop, said machine comprising means for feeding one lift lever at a time to the clinching station with said lever lying in a plane at right angles to the principal plane of the cap and presenting the lift lever to the cap with the 20 rolled edge of the cap extending between said lug of the lever and the open loop end of the lever, reciprocable clinching means at said station and moving in a plane at substantially right angles to the lug for bending the lug toward an 25 opposing portion of the rim edge for a distance to loosely confine the rolled portion of said rim edge within the loop between said lug and said free extremity of one leg of the loop so that the lift lever is pivotally attached to the rim of the cap. 30

3. In a machine as set forth in claim 1 wherein there is means for timing said feeding means to feed a lift lever into position relative to said cap when the clinching die is out of its effective clinching position. 35

4. In a machine as set forth in claim 1 wherein there is means for timing said feeding means to feed a lift lever into position relative to said cap when the clinching die is out of its effective clinching position and for maintaining the feeding means in its extreme feeding position during the clinching operation to support the lift lever in its feed position. 40

5. In a machine for applying lift levers to the rim edge of plug covers for containers, magazine 45 means for intermittently delivering levers one at a time to feeding position, means for feeding plug covers to a clinching station, a reciprocating clinching die at said station for bending a lug projecting from the lift lever about a portion of 50 the plug cover rim, and means for feeding one lift lever at a time from feeding position to the edge of said cover at said station including a member to associate them with the bendable lug or projection thereon in position, to be operated upon by 55 said clinching die, when said clinching die is out of its effective operating clinching position, said cover feeding means including a guide for guiding the covers to the clinching station, and said associating member having a to and fro movement, 60 and being arranged to grip a cover between it and said guide when the associating member is in its extreme associating position and during the clinching operation.

6. In a machine for applying lift levers to the 65 rim edge of plug covers for containers, means for feeding plug covers to a clinching station, a reciprocating clinching die at said station for bending a lug projecting from the lift lever about a portion of the plug cover rim, and means for 70 feeding one lift lever at a time from feeding position to the edge of said cover at said station to associate them with the bendable lug or projection thereon in position to be operated upon by said clinching die, when said clinching die is 75

out of its effective operating clinching position, means for limiting the movement of the cover fed to the clinching station, said limiting means comprising a stop member raised into and out of the plane of movement of the cover synchronously with the operation of the clinching die.

7. In a machine for applying lift levers to the rim edge of plug covers for containers, means for feeding plug covers to a clinching station, a reciprocating clinching die at said station for bending a lug projecting from the lift lever about a portion of the plug cover rim, and means for feeding one lift lever at a time from feeding position to the edge of said cover at said station to associate them with a bendable lug or projection thereon in position to be operated upon by said clinching die, when said clinching die is out of its effective operating clinching position, means for limiting the movement of the cover fed into the clinching station, said limiting means comprising a stop member adapted to engage the rim of the cover and raised out of the plane of the cover after the clinching operation and moved downwardly into the plane of said cover when the clinching die is retracted from the clinching position, whereby the cover feeding means will advance the next succeeding cover to the clinching station after each clinching operation.

8. In a machine for applying lift levers to the rim edge of plug covers for containers, magazine means for intermittently delivering levers one at a time to feeding position, means for feeding

plug covers to a clinching station, a reciprocating clinching die at said station for bending a lug projecting from a lift lever about a portion of the plug cover rim, and means for feeding one lift lever at a time from feeding position to the edge of said cover at said station including a member to associate them with the bendable lug or projection thereon in position to be operated upon by said clinching die, when said clinching die is out of its effective operating clinching position, said magazine means comprising a vertical chute overlying said associating member and normally closed by the latter when the same is in its extreme article associating position; an oscillatory finger arranged to be moved in and out of said chute by the movement of said associating member for holding all the articles in said chute except the last against further movement in said chute, when said associating member uncovers the bottom of said chute.

9. In a machine as set forth in claim 1 further characterized by a magazine comprising a chute through which the lift levers are fed end to end to said lever feeding means; and said lever feeding means including a member for associating a lift lever with a cap and normally closing the end of said chute, when in its associating position, and uncovering the end of said chute, when moved from its associated position, for permitting one of said levers to drop into position to be moved in associated position with said cover.

JOHN L. CARD.
